SERVICE TRAY

Samuel Bloomfield, Chicago, Ill.

Application September 18, 1936, Serial No. 101,408

2 Claims. (Cl. 311—22)

This invention relates to certain novel improvements in service trays and supports therefor, and more particularly to a service tray designed and adapted for use in connection with an automobile whereby the service tray is detachably supported from a door frame or other part of the automobile during use.

One of the primary objects of this invention is to provide a service tray and support therefor which will be highly efficient in use and economical in manufacture, and one readily adaptable for connection and detachment from a door or other object of an automobile.

A still further object of the invention is to provide a support for a service tray of the character hereinafter described which may be readily collapsed and extended.

Other objects will appear hereinafter.

The invention consists in the novel combination and arrangement of parts to be hereinafter described and claimed.

The invention will be best understood by reference to the accompanying drawing showing the preferred form of construction, and in which:

Fig. 1 is an end view of the invention, illustrating the same attached to a stationary object such as, for example, the door of an automobile;

Fig. 2 is a cross-sectional detail view of the same;

Fig. 3 is a perspective view of the invention illustrating the bottom thereof;

Fig. 4 is a perspective view of the invention similar to that shown in Fig. 3, but showing the support for the tray in collapsed position;

Fig. 5 is a fragmentary sectional detail view of the same taken substantially on line 5—5 of Fig. 2; and

Fig. 6 is a fragmentary sectional detail view similar to that shown in Fig. 5, but taken substantially on line 6—6 of Fig. 4, the section, however, being inverted from its position in Fig. 4.

Referring now more particularly to the drawing, forming a part of this application, and in which the preferred form of construction of the invention is illustrated, 10 indicates a service tray of a conventional construction and design.

Adjacent the opposite end portions 11 of this tray 10 I attach in parallel spaced relation with respect to each other supporting legs 12 formed as an integral part of an elongated bar member 13 secured to the bottom 14 of the tray by suitable connecting elements such as are indicated at 15. These legs 12 extend downwardly from the bottom 14 of the tray 10, and are preferably covered with a tubing 16 of rubber or the like,

whereby to prevent marring or scratching the object from which the tray is suspended.

These supporting legs 12 in addition to providing means for connection to the door 17 of an automobile, also serve to support the tray 10 in a substantially horizontal plane when positioned upon a supporting structure such as, for example, a table or the like.

Secured to the tray 10 between the bars 13 and in parallel spaced relation with respect thereto is 10 a guide member 18 formed substantially channel-shaped in cross-section to provide oppositely disposed guiding grooves 19. Slidably positioned between these grooves 19 is a brace member or arm 20, the upper end of which is provided with a 15 transversely extending pin 21, the ends 22 of which are disposed and ride in the grooves 19 when the brace arm is collapsed or extended in the manner shown in Figs. 1 and 2.

At the end portion 23 of the guide member 18 20 is a depending lip 24 which is adapted to engage the pin 21 to prevent accidental displacement of the pin 21 from the grooves 19. The opposite end portion 25 of the brace arm 20 is provided with an extended portion 26 outwardly of the 25 pin 21 whereby when the brace arm 20 is disposed in extended position in the manner shown in Figs. 1 and 2, this extended portion will engage the base 27 of the guide member 18 and thereby limit the pivotal movement of the brace 30 arm 20 in extended position shown.

Adjacent the pin 21 is a depending lip 28 preferably struck from the brace arm 20 to provide a finger piece whereby to facilitate collapsing and extending the tray supporting structure hereto- 35 fore described and shown in the drawing.

Formed on the side walls of the brace arm 20, such as for example, 29, is an obstructing lip 30 which is adapted to engage in the groove 19 of the guide member 18 such as indicated at 31, 40 and wedge the brace arm 20 in the guide member 18 in the manner shown in Fig. 4, whereby to prevent accidental displacement of the brace 20 when not in use as a brace member for the 45 tray 10.

To complete the invention, I attach to the tray or lower end portion 32 of the brace arm 20 a rubber knob or bumper 33 which performs the two-fold function of frictionally bearing against 50 the adjacent portion of the door 17 and preventing the marring or scratching of the surface of the door 17.

From the description herein it will be apparent that I provide a service tray and support there- 55

for which is economical in manufacture and one which will be highly efficient in use.

While I have illustrated and described the preferred form of construction for carrying my invention into effect this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

15. 1. A service tray having secured thereto means adapted for detachable connection to the upper edge of a vehicle door and adjustable brace means including an elongated channel member attached to the bottom of said tray and having opposite edge portions formed to provide oppositely disposed longitudinally extending grooves, an elongated brace arm of channel shaped cross section receivable in said channel member between said grooves thereof, a pin extended laterally through an end of said brace arm and having its ends received in said opposite grooves, said end of the brace arm being slanted to permit moving said arm about said pin as an axis from a position substantially within said channel member into a position at substantially 45 degrees thereto, and means at the ends of said channel member for preventing movement of said brace arm and pin means out of the axial ends thereof.

2. A service tray having secured thereto means adapted for detachable connection to the upper edge of a vehicle door and adjustable brace means including an elongated channel member attached to the bottom of said tray and having opposite edge portions formed to provide oppositely disposed longitudinally extending grooves, an elongated brace arm of channel shaped cross section receivable in said channel member between said grooves thereof, a pin extended laterally through an end of said brace arm and having its ends received in said opposite grooves, said end of the brace arm being slanted to permit moving said arm about said pin as an axis from a position substantially within said channel member into a position at substantially 45 degrees thereto, and means at the ends of said channel member for preventing movement of said brace arm and pin means out of the axial ends thereof.

20. 2. A service tray having secured thereto means adapted for detachable connection to the upper edge of a vehicle door and adjustable brace means including an elongated channel member attached to the bottom of said tray and having opposite edge portions formed to provide oppositely disposed longitudinally extending grooves, an elongated brace arm of channel shaped cross section receivable in said channel member between said grooves thereof, a pin extended laterally through an end of said brace arm and having its ends received in said opposite grooves, said end of the brace arm being slanted to permit moving said arm about said pin as an axis from a position substantially within said channel member into a position at substantially 45 degrees thereto, and means at the ends of said channel member for preventing movement of said brace arm and pin means out of the axial ends thereof, said brace arm having means spaced substantially away from said pin member toward the opposite end of said brace arm and receivable in said channel member to prevent pivotal movement of the brace arm out of the channel member.

SAMUEL BLOOMFIELD. 30
